CLAIM

The ornamental design for a protective glove, substantially as shown and described.

DESCRIPTION

FIG. 1 is a front view of a glove embodying the new design; FIG. 2 is a back view of a glove embodying the new design; FIG. 3 is a right view of a glove embodying the new design; FIG. 4 is a left view of a glove embodying the new design; FIG. 5 is a top view of a glove embodying the new design; and, D20/33

FIG. 6 is a bottom view of a glove embodying the new design. All figures illustrate right hand protective glove designs of the present invention, it is to be understood that the invention includes left hand protective glove designs which would be illustrated as mirror images of any or all of the views shown in FIGS. 1-6.

The broken lines shown on the drawings is included for the purpose of illustrating conventional stitching and forms no part of the claimed design.
